(57) CLAIM

I claim the ornamental design for a pen with a transparent reflection ornament as shown and described.

DESCRIPTION

FIG. 1 is a front side view of a pen with a transparent reflection ornament showing the design;

FIG. 2 is a left side view thereof;

FIG. 3 is a top plan view thereof;

FIG. 4 is a rear side view thereof;

FIG. 5 is a right side view thereof;

FIG. 6 is a perspective view thereof; and,

FIG. 7 is an enlarged perspective view thereof.

The body of a pen shown in broken lines in the drawings is environmental matter and forms no part of the claimed design.
